CLAIM

The ornamental design for a guitar, as shown and described.

DESCRIPTION

FIG. 1 is a front elevational view of a guitar showing my new design;

FIG. 2 is a bottom plan view thereof;

FIG. 3 is a right-side elevational view thereof;

FIG. 4 is a rear elevational view thereof;

FIG. 5 is a top plan view thereof;

FIG. 6 is left-side elevational view thereof; and,

FIG. 7 is a perspective view thereof.

The broken line showing of the guitar neck, headstock and hardware is for illustrative purposes only and forms no part of the claimed design.
